(57) **CLAIM**

The ornamental design of footwear, as shown and described.

DESCRIPTION

FIG. 1 is a side and bottom perspective view of footwear; FIG. 2 is a front elevation view thereof; FIG. 3 is a rear elevation view thereof; FIG. 4 is a side elevation view thereof; FIG. 5 is an opposite side elevation view thereof; FIG. 6 is a top plan view thereof; and, FIG. 7 is a bottom plan view thereof.

The broken lines in figures indicate the boundaries of portions of the design which are not part of the claimed design.

The different stippling patterns in areas of design are meant to depict contrast between those areas and not differences in color or material.
